UNITED STATES PATENT OFFICE.

CHARLES A. MAZZIE, OF DETROIT, MICHIGAN.

BANK-PROTECTING DEVICE.

Application filed April 4, 1921. Serial No. 458,585.

To all whom it may concern:

Be it known that I, CHARLES A. MAZZIE, a citizen of the United States, residing at Detroit, county of Wayne, State of Michigan, have invented a certain new and useful Improvement in Bank-Protecting Devices, and declare the following to be a full, clear, and exact description of the same, such as will enable others skilled in the art to which it pertains to make and use the same, reference being had to the accompanying drawings, which form a part of this specification.

This invention relates to bank protecting devices and the object of the invention is to provide a means for protecting a bank against robbery and holdups. Another object of the invention is to provide a device for protecting a bank cage consisting of a grille which may be closed to entirely enclose the said cage. Another object of the invention is to provide a grille for a bank cage consisting of a series of vertically positioned parallel shutters adapted to be closed instantly from any point in the cage. Another object of the invention is to provide a mechanism whereby a bank cage may be entirely enclosed, the operation of the mechanism also closing a pair of doors provided for the teller's window, it being impossible to open the said doors from the outside of the cage when once closed. A still further object of the invention is to provide a grille for a bank cage consisting of shutters pivoted to turn on a vertical axis, which may be instantly closed from the interior of the cage by a slight pull on a rope provided therein. These objects and the several novel features of the invention are hereinafter more fully described and claimed and the preferred form of construction by which these objects are attained is shown in the accompanying drawings in which—

Fig. 1 is a view from the interior of the cage showing the shutters and doors for the teller's window in the closed position.

Fig. 2 is a view of the upper end of the corner post at the left of Fig. 1 partly broken away to show the construction.

Fig. 3 is a section through the corner post opposite to that shown in Fig. 2.

Fig. 4 is a section taken on line 4—4 of Fig. 2 with the shutters shown in the open position.

Fig. 5 is a section similar to Fig. 4 showing the shutters in the closed position.

Fig. 6 is a section showing the controlling mechanism for the shutters.

Fig. 7 is a section taken on line 7—7 of Fig. 6.

Fig. 8 is a view of the spring tension adjusting mechanism, provided in the lower end of the corner post.

Fig. 9 is an enlarged section taken on line 9—9 of Fig. 7.

Fig. 10 is a section taken on line 10—10 of Fig. 5.

Fig. 11 is a perspective view of one of the supports for the upper end of the shutters.

Fig. 12 is a view of the doors for closing the teller's window looking from the interior of the cage and shown in the closed position.

Fig. 13 is a section taken on line 13—13 of Fig. 12.

Fig. 14 is an enlarged section taken on line 14—14 of Fig. 12.

Fig. 15 is an enlarged section taken on line 15—15 of Fig. 13.

Fig. 16 is an elevation of one of the supports for the lower ends of the shutters.

Fig. 17 is a plan view of the spring retaining clip for use with the door closing mechanism.

Fig. 18 is a side elevation thereof.

The bank cage as shown in Fig. 1, consists of a solid lower wall 1 which is usually made of marble or the like and provided with a counter 2. On the upper part of the portion 1 is a grille 3 which, as shown in Fig. 2, consists of a corner post 4 and a series of metal shutters 5 which may be utilized in place of the usual bank grille. Supported on the corner post 4 is an angle iron member 6 which is provided with a series of apertures therethrough to receive the bearing member 7. These bearing members, as shown more particularly in Fig. 10, are each slotted to receive the upper end of a shutter 5 and are secured thereto by screws or rivets 8. As shown in Figs. 10 and 11 each member 7 is provided with a flange 9 adapted to engage against the angle iron member 6 and the members 7 are also provided with a rounded portion 10 fitting the apertures in the angle iron member 6 and the upper end 11 thereof is flattened and adapted to fit apertures therefor in the members 12 and a washer 13 is then secured to the part 11 by the screws 14 to hold the levers 12 thereon. At the lower edge of the grille and supported on the adjacent

75

95

100

105

110

edge of the counter 2 is a bar 15 apertured to receive the bearing members 16 which are shown more particularly in Fig. 16. These members 16 are formed in two halves and are secured to the shutters 5 by the screws 17 and are each provided with a flange 18 and a lower rounded portion 19 fitting in the said bar 15. As shown in Fig. 5 a movable bar 20 extends across the front 10 of the cage at the top and the outer end of each lever 12 is pivotally secured to the said bar. The end of the bar 20 adjacent the corner post 4 is enlarged and provided with an aperture 21. Within the corner post 4, 15 as shown in Fig. 6, is a tubular shaft 22 having a solid bearing end 23 secured therein adapted to rotate on the conical head of the bolt 24 in the bearing 25. The shaft 22 at the upper end, as shown in Fig. 2, is provided with a member 26 secured therein, the member 26 being formed with an arm 27 having a pin in the outer end thereof on which is rotatably mounted rollers 28 and 29. Across the end of the cage is a bar 30 20 to which the levers 12 for the shutters at the end of the cage are pivotally connected as shown in Figs. 4 and 5. This bar 30 is provided with an enlarged end having an aperture 31 therein. As shown in Fig. 2, 25 the roller 28 is rotatable in the aperture 21 of the bar 20 and the roller 29 is rotatable in the aperture 31 in the bar 30 and a bearing 32 is provided within the corner post 4 in which the tubular shaft 22 is rotatable. 30 When the shutters are in the open position 35 as shown in Fig. 4, the lever 27 may be given a quarter turn to the left to the position shown in Fig. 5, by a mechanism hereinafter described, which moves the bar 30 to the left thereby closing the shutters in 40 the end of the cage and moves the bar 20 at the same time to close the shutters in the front of the cage. The mechanism for turning this shaft is shown more particularly 45 in Figs. 6, 7 and 9 and is enclosed within a sheet metal box or casing 33, the bearing 25 being riveted to the bottom of the box by the rivets 34. As shown in Figs. 6 and 7 secured to the tubular shaft 22 by a set 50 screw 35 is a lever 36 having a handle 37 and an adjusting screw 38 which is adapted to contact the rubber bumper 39 when the lever is moved to the position shown in dotted lines in Fig. 7. About the shaft 22 55 is a coiled spring 40 the lower end of which is turned down and extends between the set screw 35 and lever 36 as shown in Figs. 6 and 7. The upper end of the said spring is provided with a horizontal extending 60 portion 41 adapted to engage in the slot 42 as shown in dotted lines in Fig. 8. Should the tension of the spring be not sufficient to turn the lever 36 to the dotted position shown in Fig. 7 when released, the 65 tension thereof may be increased by plac-

ing the end 41 in any one of the series of notches 43 shown in Fig. 8. As shown in Fig. 7 a latch 44 is provided which is secured to a shaft 45 rotatably mounted in a bracket 46 and a spring 47 is interposed between the end of the latch 44 and the adjacent wall of the casing 33 tending to yieldingly resist movement of the lever 44 to the dotted position shown in Fig. 7. The lower end of the shaft 45 is supported in a 70 bracket 48 and on the lower end of the shaft is a lever 49 pivotally secured at the outer end to a lever 50. This lever 50 is pivotally secured to an arm 51 and is provided with a shoulder 52 against which a set screw 53 is 75 adapted to engage. This set screw 53 is threaded through a lug 54 on the lever 51 and the lever 51 is provided with a collar 55 seating on the flange 56 of a metal sleeve 57, as shown more particularly in Fig. 9. 80 This sleeve 57 extends downwardly through the bottom of the casing 33 and through a portion 58 of the counter 2 which is usually of marble or like material. A washer 59 is interposed over the depending end of the 85 sleeve 57 and is secured in place by a nut 60 which also secures the sleeve 57 in place. The lever 51 is formed integrally with a shaft 61 which is provided with a squared lowered end 62 on which is positioned a 90 lever 63 to which a rope 64 is secured. A nut 65 is threaded on the lower end of the shaft 61 and holds the lever 63 in position, a lock nut 66 being provided to prevent removal of the nut 65. The rope 64, as shown 95 more particularly in Fig. 1, extends along beneath the counter 2 and passes over a pulley 67 and thence downward around a pulley 68 and thence parallel with the floor beneath the teller's window and around a pulley 69. The portion of the rope 64 between the pulleys 68 and 69 is adapted to be stepped on by the teller to pull the lever 63 shown in Fig. 9 and close the shutters 100 and doors for the teller's window. The 105 rope 64 extends from the pulley 69 over a pulley 70 and thence along beneath the counter 2 where it may be easily reached by hand and pulled. Where the cages are arranged in a bank side by side so that the front of each cage is the only part exposed the rope 64 continues along the front and beneath each teller's window as shown in Fig. 1. In a small bank where the cage is exposed on three or four sides the rope 64 110 extends around the four sides of the cage beneath the counter 2 the opposite end of the rope being secured to the lug 71 of the washer 59 which is solidly secured in position so that a pull on the rope is applied to move the lever 63 only. In case the cage is exposed on three sides the cage is provided with a corner post 72 adjacent the end of the bar 30 shown in Fig. 3. A bracket 73 115 is secured to the post 72 and supports a bell 120 125 130

crank 74 having a depending pin 75 in one end thereof. The bar 30 is provided with a slot in the end thereof shown in dotted lines in Fig. 3, in which the pin 75 engages, 5 the bar 30, lever 12 and shutters being in the closed position in Fig. 3. On the opposite arm of the bell crank 74 is a depending pin 76 engaging in a slot 77 in the end of a bar 78 to which the levers 12 on the 10 third side of the cage are pivoted. When the shutters are opened by moving the bar 30 from the position shown in Fig. 5 to that shown in Fig. 4 the bar 30 shown in Fig. 3 is moved toward the right thus turning the bell crank 74 and moving the bar 78 to open 15 the shutters on the third side of the cage. To provide a closing means for the fourth side of the cage a device similar to that shown in Fig. 3 is provided for the opposite end of the bar 20 shown in Fig. 5. As 20 shown in Figs. 12 and 13 a pair of doors 79 are provided for closing the teller's window and are hinged at 80. These doors are of heavy sheet metal and when the doors 25 are open, as shown in dotted lines in Fig. 13, a latch member 81 engages in a notch in the upper edge of each door and holds the door open against the tension of the spring 82. As shown in Fig. 15 the latch member 30 81 is mounted on the squared end 83 of a member 84 and is held in place by a screw head 85, the member 84 being rotatably mounted in a frame member 86 about the opening in the teller's window and a shutter 5 being secured in the upper end of each member 84. The shutter 5 for each member 84 is controlled by the bar 20 shown in Fig. 5 and is turned with the remainder of the shutters about the cage, the turning of the 35 shutters for the members 84 moving the members 81 from the position shown in dotted lines in Fig. 13 to the position shown in full lines therein, thereby releasing the doors to close by the springs 82. The 40 springs 82, as shown more particularly in Fig. 12, consist of two oppositely wound coils connected together at the center by a portion 87. The opposite ends of the coils are secured to the sheet metal frame 88 at each side of the teller's window by clips 89. Secured to each door on the inner side is 45 a toothed member 90 shown more particularly in Fig. 14. The member 90 shown in Fig. 14 is secured to the door at the right 50 of Figs. 12 and 13 and due to the center of the spring 82 being behind the hinge 80 the end of the spring 87 will be in the dotted position 87^a when the door is opened. As 55 the door is closed by tension of the spring 82 the portion 87 of the spring moves backward notch by notch due to the spring center being behind the hinge 80 and due to this engagement of the spring 87 in the teeth 91 it is impossible to open the doors from 60 the outside when once closed. The doors 65 79 are each provided with an arcuate notch forming an aperture 92 when closed and, to hold the adjacent end of the coils of the spring 82 in position I provide a clip 93 as 70 shown in Figs. 17 and 18. These clips are secured to the frame 88 and are provided with ends 94 engaging in each spring coil. By this construction should pressure be applied to the outer faces of the doors 79 the members 87 will be held from endwise 75 movement by the clips 93 which hold the spring coils in position and thus the doors are prevented from being opened. A lug 94, as shown in dotted lines in Fig. 12, is 80 provided against which the doors 79 may shut, the lug 94 providing a stop for the said doors. The doors 79 are also provided with lugs 95 adapted when opened to engage over a lug 96 on a stationary frame part 97, and a pin may be inserted through 85 the apertures in the lugs 95 and 96 to hold the doors open prior to engaging the latch members 81 in the notches therefor in the doors and a lug 98 may be provided to hold the said pins when not in use. The aperture 92 is provided in the doors so that should a robber pass his hand and gun into the teller's window the shutters may be closed by stepping on the rope 64 which 90 also allows the doors to close under tension of the springs 82, the portion of the doors about the aperture 92 engaging the robber's wrist. To prevent the robber from shooting the teller a sheet metal armour plate 99 is provided slidably mounted in ways 100 100 provided on the under side of the counter 2. A spring 101 is secured to the plate 99 at the lower end and to the counter 2 at the upper end, the spring being under tension and being adapted to raise the plate 99 105 through a slot 102 provided in the counter 2. To hold the plate 99 from moving upward in the slot 102 when the shutters and doors are opened I provide a pair of levers 103 pivoted at 104 on the counter 2 and being adapted to be placed in the position shown in dotted lines in Fig. 13 when the doors are open, the ends 105 engaging over 110 the upper edge of the plate 99 at each end. When the doors are closed due to the end 106 of the members 103 being in the path of movement of the doors the same are turned to the position shown in full lines in Fig. 13, which moves the ends 105 off 115 from the edge of the plate 99 and allows the same to move upward by action of the spring 101, the plate being positioned between the teller and the robber before the doors 79 are entirely closed. A hinged plate 120 may be provided over the slot 102 so that the counter is provided with a smooth surface the hinged plate being adapted to turn out of the way when the plate 99 is moved upward by the spring 101. 125 In operation the lever 36 is locked in the 130

position shown in Figs. 6 and 7 by the latch member 44 the shutters at this time being opened as shown and the doors for the teller's window being also in the open position indicated by dotted lines 79 in Fig. 13. The doors 79 are held in the open position by the latch members 81 which, when the shutters are opened, are in the dotted position shown in Fig. 13, and which hold the doors open. When the lever 36 is in the position shown in Fig. 7 the arm 27 in the upper end of the tubular shaft 22 and levers for controlling the shutters are in the open position shown in Fig. 4. When the parts are in the open position as described the appearance of the cage is not unlike the ordinary bank cage, but should a robber enter the bank and attempt to hold up the teller, the teller may step on the rope 64 directly beneath the teller's window, or anyone within the cage may pull on the rope which extends beneath the counter. This movement of the rope turns the lever 63, shown more particularly in Fig. 9, which turns the lever 51 which moves the lever 50 endwise and thus moves the lever 49 and latch 44 to the position shown in dotted lines in Fig. 7 thereby releasing the lever 36 to action by the springs 40, the said spring being of sufficient tension to turn the lever 36 to the position shown in dotted lines in Fig. 7, which turns the shaft 22 and arm 27 from the position shown in Fig. 4 to that shown in Fig. 5, the said movement of the arm 27 moving the rods 20 and 30 to turn the shutters 5 to the closed position as will be readily understood and as shown in Fig. 5. The movement of the rod 20 also turns the shutters 5, shown in Fig. 12, which moves the latch member 81 to the position shown in full lines in Fig. 13 thus releasing the doors 79 to action by the springs 82 which instantly close the doors. It will be noted that should the robber, in holding up the teller, advance his gun and hand through the teller's window the doors 79 which are each recessed will engage the robber's wrist in closing and the robber's wrist will be tightly held in the aperture 92 it being impossible for the robber to open the doors on account of the spring ends 87 engaging in the teeth 91 of the members 90. To prevent the teller from being shot I provide a shield 99 which is held in the lower position shown in Fig. 12 by the ends 105 of the levers 103 engaging over the upper edge thereof. Before the doors are closed these levers 103 are positioned in the path of movement of the doors, as shown in dotted lines, and as the doors swing closed the levers are turned to the position shown in full lines in Fig. 13 which moves the ends of the levers off from the edge of the shield 99 and allows the same to spring up through the slot 102 under action of the spring 101. This shield is positioned between the robber and teller and prevents the teller from being shot by the robber. The shutters and doors are closed simultaneously and before the doors have become completely closed the shield 99 is released to action by the spring 101 as will be readily understood, so that the cage is entirely closed instantaneously. The shutters 5, as shown in Fig. 13, are made of metal plate of sufficient thickness to withstand gun shots and the ends of the shutters 5 overlap, so that a continuous wall is provided when the cage is closed. A glass plate 107 is usually provided on the front of the cages and prevents the robber from inserting a gun or lever between the shutters when open to prevent the same from closing which might be done if the glass plates were not provided. To again set the device the spring ends 87 are removed from the toothed members 90 and the doors are swung open until the lugs 95 thereon engage over the stationary lugs 96. At this time a pin is inserted through the lugs 95 and 96 to hold the doors open and the spring ends 87 are released. While the doors are thus held open the shield 99 is pushed down through the slot 102 against the tension of the spring 101 and the levers 103 are turned to the position shown in dotted lines in Fig. 13, the ends 105 of the levers 103 engaging over the upper edge of the shield 99 and holding the same in the depressed position. The latch member 44 and levers 49, 50 and 51 are returned to the original position by the spring 47 after each actuation and to again open the shutters the door in the casing 33 is opened, the upper cover for the casing opening outwardly with the door as will be seen. The lever 36 is then moved by means of the handle 37 from the position shown in dotted lines to the position shown in full lines in Fig. 7 against the tension of the spring 40. As the lever 36 is moved to the position shown in full lines the latch 44, under action by the spring 47, engages over the end thereof and locks the lever in position. This movement of the lever 36 from the dotted position to the locked position turns the arm 27 from the position shown in Fig. 5 to that shown in Fig. 4 thus opening the shutters by means of the rods 20 and 30. As the shutters are opened the latches 81, shown more particularly in Fig. 13, are moved from the position shown in full lines in Fig. 13 to the position shown in dotted lines at which position the latches engage a notch in the upper edge of each door and lock the said doors in the open position. At this time the pin may be withdrawn from the lugs 95 and 96 and the doors will be held in the open position by the latches 81, the entire device at this time being set in position for closing by a pull on the rope 64. It is to be noted that the cage may be entirely enclosed by this device and should it be necessary a sheet metal 130

top may be provided for the cage but is unnecessary where the grille of the cage extends to the ceiling of the building in which it is used.

5 From the foregoing description it becomes evident that the device is very efficient in operation, of positive action and strong construction, is easily operated and reset and provides a device which accomplishes the objects desired.

Having thus fully described my invention, its utility and mode of operation, what I claim and desire to secure by Letters Patent of the United States is—

15 1. A bank protecting device comprising a grille for a bank cage consisting of a series of vertical shutters adapted to turn in a horizontal plane, the grille being provided with an opening, a pair of spring actuated doors for closing the opening, a shutter adjacent each door being provided with means for holding the doors in the open position when the shutters are open, a spring tending to close the shutters, releasable means for holding the shutters open against the tension of the spring, and means for actuating the releasing mechanism from any point within the cage, the closing of the shutters releasing the said doors to actuation by the respective springs.

2. A bank protecting device comprising a grille for a bank cage consisting of a series of shutters each adapted to turn on the longitudinal axis thereof, an opening in the said grille, a pair of spring actuated doors adapted to close the said opening, means controlled by the shutters for holding the doors open when the shutters are open, and means for releasing the doors to actuation by the respective springs when the shutters are closed.

3. A bank protecting device comprising a grille for a bank cage consisting of a series of vertical shutters adapted to turn in a horizontal plane, a frame member supporting the shutters at each end, a series of levers secured to the said shutters, a slotted bar to which the said levers are pivoted, a

shaft having an arm on the upper end thereof, a pin on the said arm engaging in the slot in the bar, a lever for turning the shaft to move the bar longitudinally to open or close the shutters, a spring tending to turn the shaft to close the shutters, and releasable means engaging the said lever adapted to prevent closing of the shutters by the spring.

4. A bank protecting device comprising a grille for a bank cage consisting of a series of shutters each adapted to turn on the longitudinal axis thereof, an opening in the said grille, a pair of spring actuated doors adapted to close the said opening, a ratchet device on each door preventing opening of the doors against the tension of the spring, a latch for each door secured to an adjacent shutter and adapted to hold the doors open when the shutters are open, and means for releasing the said latches as the shutters are closed.

5. A bank cage comprising an enclosed lower portion provided with a counter having a slot therein, a grille for the upper part of the cage comprising a series of shutters adapted to turn on their longitudinal axes, an opening in the said grille, a pair of spring actuated doors for closing the said opening, a spring actuated shield behind the door movable through the slot in the said counter, a lever pivoted to the counter at each end of the slot having a portion adapted to extend over the edge of the shield, the opposite ends of the levers extending in the path of movement of the said doors, a latch normally holding each door open when the shutters are open, and means for releasing the doors to actuation by the respective springs as the shutters are closed, the closing of the doors moving the said levers to release the shield to upward movement through the slot by action of the respective spring.

In testimony whereof, I sign this specification.

CHARLES A. MAZZIE.
